[57] **CLAIM**

The ornamental design for a dishrack and cutlery basket, as shown and described.

DESCRIPTION

FIG. 1 is a first perspective view of the design according to the invention;

FIG. 2 is a second perspective view of the design of FIG. 1;

FIG. 3 is a front view of the design of FIG. 1;

FIG. 4 is a back view of the design of FIG. 1;

FIG. 5 is a left side view of the design of FIG. 1;

FIG. 6 is a right side view of the design of FIG. 1;

FIG. 7 is a top view of the design of FIG. 1;

FIG. 8 is a bottom view of the design of FIG. 1;

FIG. 9 is a cross sectional view taken through the center and in the direction of 9—9 of FIG. 1, with the cutlery basket omitted for ease of illustration;

FIG. 10 is a cross sectional view taken at the end and in the direction of 10—10 of FIG. 1, with the cutlery basket omitted for ease of illustration;

FIG. 11 is a perspective close up view of the cutlery basket of the design of FIG. 1, provided to improve the clarity of the cutlery basket aspect of the design;

FIG. 12 is a left side view of the cutlery basket of FIG. 11; FIG. 13 is a front view, the back view being a mirror image thereof, of the cutlery basket of FIG. 11;

FIG. 14 is a right view of the cutlery basket of FIG. 11;

FIG. 15 is a top view of the cutlery basket of FIG. 11; and, FIG. 16 is a bottom view of the cutlery basket of FIG. 11.
